A. M. EPSTEIN

DENTAL TRAY

Filed April 25, 1924

WITNESS:

John R. Ketchel.

INVENTOR

Albert M. Epstein

BY

Augustus B. S. Wroughton

ATTORNEY.

UNITED STATES PATENT OFFICE.

ALBERT M. EPSTEIN, OF ELMIRA, NEW YORK.

DENTAL TRAY.

Application filed April 25, 1924. Serial No. 708,841.

To all whom it may concern:

Be it known that I, ALBERT M. EPSTEIN, a citizen of the United States, residing at Elmira, in the county of Chemung and ⁵ State of New York, have invented a new and useful Improvement in Dental Trays, of which the following is a specification.

The principal objects of the present invention are to provide a comparatively inexpensive dental tray, so inexpensive that it can be used once and then thrown away; to provide a dental tray which, among other reasons than the one stated, is sanitary; to provide that the operator in the use of the ¹⁰ tray may readily not only hold the same but also be advised of the temperature or condition of the plastic material and in addition may be assured that the plastic material will not overflow in the direction of the patient's throat; to avoid disturbing or contacting with either of the lip muscles of the patient thereby insuring a good impression; to avoid absorption of moisture from the plastic material where the latter is ¹⁵ mixed wet; to insure the retention of heat where the plastic material is used warm; and to, in general, provide an improved tray for dentists' use.

Other objects of the invention will appear ²⁰ from the following description and the invention, generally stated, may be said to comprise a one-piece died or stamped dental tray consisting of chemically hardened fiber and having an open ended container ²⁵ for plastic material and a handle centrally channelled in the direction of the bottom of the container and communicating with the container to accommodate lip muscles and to provide for overflow of plastic material and ³⁰ to afford a finger-hold and feel, said fiber being non-absorbent in respect to plastic material and also a non-conductor of heat or cold. The invention also comprises the improvements to be presently described and ³⁵ finally claimed.

In the accompanying drawings I have chosen from many forms of dental trays in which my invention may be embodied two characteristic forms in which the invention ⁴⁰ is embodied.

In the drawings—

Figure 1 is a top or plan view of a dental tray embodying features of the invention.

Fig. 2 is a section on the line 2—2 of ⁵⁵ Fig. 1.Fig. 3 is a section on the line 3—3 of ⁶⁰ Fig. 1.

Fig. 4 is a top plan view of a modification, and

Fig. 5 is a section on the line 5—5 of ⁶⁵ Fig. 4.

The dental tray consists of one piece and it is died or stamped. The dental tray is made of chemically hardened fiber. Chemically hardened cotton or wood fiber is a ⁷⁰ known commodity. The tray includes a container 1 open at the end 2. It happens to be shown with a dome-shaped central portion 3. This container receives plastic material such as moist plaster of Paris or warm ⁷⁵ wax. The handle 4 is centrally channelled in the direction of the bottom of the container and the channel 5 communicates with the container as at 6. By this arrangement space is provided as at 6 for the accommodation ⁸⁰ of the muscle of either the upper or lower lip. This space also affords an overflow away from the throat of the patient for plastic material and the thumb or finger of the operator having a hold in the channelled portion of the handle is in position to feel the overflowing plastic material, thus permitting the operator to ascertain its temperature or condition of dryness. The tray is non-absorbent in respect to moisture in ⁸⁵ the plastic material which in the case of plaster of Paris is advantageous, and the tray is also a non-conductor of heat and cold which is advantageous in the case of ⁹⁰ wax or like material.

The structure of the modification shown in Figs. 4 and 5 is as has been above described except that the container 1^a is open at the ends 2^a and is intended for use in the provision of a partial set of teeth, where- ⁹⁵ as the tray of the other figures is intended for use in the provision of a full or complete set of teeth.

It will be obvious to those skilled in the art that modifications may be made in de- ¹⁰⁰ 100

tails of construction and arrangement without departing from the spirit of the invention which is not limited as to those matters or otherwise than as the prior art and 5 the appended claim may require.

I claim:

A one-piece died or stamped dental tray consisting of chemically hardened fiber and having an open ended container for plastic 10 material and a handle centrally channelled

in the direction of the bottom of the container and the channeled portion communicating with the container to accommodate lip muscles and provide for overflow of plastic material and to give a finger hold and 15 feel, said tray being non-absorbent in respect to plastic material and also a non-conductor of heat and cold.

ALBERT M. EPSTEIN.
